CLAIM

The ornamental design for a bottle magnet, as shown and described.

DESCRIPTION

FIG. 1 is a front elevation view of the bottle magnet showing my design and text, re-writeable text, and re-writeable text boxes in broken lines.

FIG. 2 is a back elevation view thereof;

FIG. 3 is a side elevation view thereof;

FIG. 4 is an opposite side view thereof;

FIG. 5 is a top plan view thereof;

FIG. 6 is a bottom plan view thereof;

FIG. 7 is a perspective view thereof, showing placement on a bottle in broken lines;

FIG. 8 is another upper perspective view thereof, showing placement underneath a bottle in broken lines; and,

FIG. 9 are elevation views thereof, showing placement on horizontally arranged bottles in broken lines and text, re-writeable text, and re-writeable text boxes in broken lines. The broken line features depict environmental subject matter only and form no part of the claimed design.
